UNITED STATES PATENT OFFICE.

ALBERT P. LANGLOIS, OF NORWALK, CONNECTICUT.

HEAT DISTRIBUTOR.

Application filed June 24, 1922. Serial No. 570,628.

To all whom it may concern:

Be it known that I, ALBERT P. LANGLOIS, a citizen of the United States, residing at Norwalk, in the county of Fairfield and 5 State of Connecticut, have invented new and useful Improvements in Heat Distributors, of which the following is a specification.

This invention aims to provide a heat distributing device, for use in conjunction 10 with building structures, and designed to convey or distribute heat rising from a single furnace pipe, and to two, three or four different rooms, the device being associated with a register whereby admittance of heat 15 to these rooms can be controlled.

The nature and advantages of the invention will be better understood when the following detailed description is read in connection with the accompanying drawings, 20 the invention residing in the construction, combination, and arrangement of parts as claimed.

In the drawings forming part of this application, like numerals of reference indicate similar parts in the several views, and 25 wherein:—

Figure 1 is a perspective view of a corner of a room showing a portion of the device associated with that particular room.

30 Figure 2 is a plan view of the device and the position thereof when associated with the adjacent corners of four rooms, the walls of these rooms being shown in section.

Figure 3 is a vertical sectional view taken 35 through Figure 2.

Figure 4 is a bottom plan view of the preferred form of the invention with the register removed.

40 Figure 5 is a slightly modified form of the invention.

Figure 6 is a sectional view taken on line 6—6 of Figure 5.

In Figures 1 to 4, inclusive, I have illustrated one form of the invention, which 45 is designed to distribute heat from a single furnace pipe 10 into four different rooms of the building structure, and the device illustrated for this purpose consists of a base 11 which possesses a configuration similar to a cross in plan. Depending from each section or portion of the base is a partition 12, and at the outer end of each partition 50 is arranged a supporting flange 13 which forms part of the respective portions or sections of the base as shown. It is of course

to be understood that the flanges 13 project an appreciable distance beyond the opposed sides of the adjacent partition 12. Supported upon the base 11 are attaching flanges 14 which are arranged along the sides of 60 each portion of the base, the flanges being arranged to define intersecting channels 16 to receive the adjacent walls of the building.

The device above described is adapted to be directly above the furnace pipe 10, and receives registers, one of which is disposed in each corner of the device as shown in Figure 2 of the drawings which is interposed between the pipe 10, and the heat distributor. This device is designed to provide 70 four sections, which communicate with the adjacent rooms of the structure, so that the heat rising in the pipe 10 can be admitted to any of the rooms as desired. The adjacent walls of the building structure are arranged in the channels above referred to. Manifestly, as the heat rises in the pipe 10, the same passes through the registers, striking against the bottom of the base 11, and is thereby deflected into the different rooms. 80

In Figures 5 and 6, I have illustrated a modified form of the invention wherein the heat distributor possesses substantially the same configuration as the structure illustrated in Figure 1, except that the flanges 85 20 are detachably secured to the base 21 through the medium of screw bolts 20'. This form of the invention can be used in conjunction with a building by simply cutting away the adjacent walls and sliding the 90 distributor into proper position over the heat distributing pipe of the furnace. The flanges 20 are first attached to the adjoining walls, and after the distributor has been arranged in position, the flanges are suitably secured to the base 21. The device in 95 this form of the invention is used in substantially the same manner as that described and shown in connection with the form shown in Figure 1.

100 While it is believed that from the foregoing description, the nature and advantages of the invention will be readily apparent, I desire to have it understood that such changes may be resorted to when desired as fall within the scope of what is claimed.

What I claim is:—

110 A heat distributor for adjacent rooms of building structures, comprising a base of an-

gular outline and adapted to be arranged beneath adjacent walls of the structure, a portion of the base extending into the adjacent rooms, said distributor being arranged

5 above the heat conducting pipe of a furnace, and designed to convey the hot air admitted from said pipe to the said adja-

cent rooms, flanges rising from the base and arranged to receive said walls and flanges depending from the outer edges of the base 10 to provide a supporting means therefor.

In testimony whereof I affix my signature.

ALBERT P. LANGLOIS.
